RADIOTUNER

Ernest A. Zadig, New York, N. Y., assignor to
Radio Corporation of America, New York,
N. Y., a corporation of Delaware

Application August 6, 1930, Serial No. 473,482

16 Claims. (Cl. 250—40)

This invention relates to a method of and means for adjusting the tuning of apparatus for the reception of radiant energy at different frequencies, and more particularly to a method of and means for automatically tuning a radio receiver for the reception of currents transmitted at a selected frequency or from a selected station. It is an object of this invention to provide an improved method and apparatus of the character described. Other objects and advantages of the invention will appear hereinafter.

The nature and objects of the invention will be better understood from a description of a particular illustrative embodiment thereof, and for the purpose of such description reference should be had to the accompanying drawings forming a part hereof, and in which:

Fig. 1 is a front view of a radio receiver equipped with tuning means illustrating the invention;

Fig. 2 is a view to enlarged scale of the tuning mechanism substantially as it would appear if the front panel were removed from the receiver shown in Fig. 1, the electrical control circuit being shown diagrammatically;

Fig. 3 is a sectional view taken substantially on the line 3—3 of Fig. 1, and to the same scale as Fig. 2;

Fig. 4 is a fragmentary rear view of the front panel taken substantially on the line 4—4 of Fig. 3;

Fig. 5 is a sectional view taken substantially on the line 5—5 of Fig. 4; and

Fig. 6 is a sectional view to enlarged scale taken through one of the contact members substantially on the line 6—6 of Fig. 3.

Radio receivers used for the reception of broadcast programs having tuning mechanism which is adjustable for the reception of currents of different frequencies, and at the present time the tuning mechanism of most receivers may be adjusted by means of a single control, commonly a rotatable shaft. This invention is applicable to any single control receiver. Since the radio receiver itself forms no part of this invention, no more of the receiver has been shown than is necessary for a clear understanding of the illustrative embodiment of the invention.

Customarily the tuning control shaft of a radio receiver has rigidly secured thereon an indicating disk or drum which is graduated, and which is marked, usually with a series of numbers, to provide a reference scale. The receiver may be tuned for the reception of currents from a selected station by adjusting the tuning control until the

predetermined point on the scale corresponding to the adjustment of the tuning mechanism for the reception of the desired currents registers with a reference mark. Successful operation of such a receiver presupposes on the part of the operator a knowledge of the scale reading for tuning in any desired station, as well as a certain amount of skill in accurately adjusting the tuning control.

In most instances a radio receiver which is used for broadcast reception probably is not tuned in regularly on more than eight or ten different stations, and in all probability the receiver will be used almost exclusively for the reception of currents from four or five of those stations.

It is customary to designate radio transmitting stations by arbitrary arrangements of symbols, usually letters, which arrangements, whether of letters or other symbols, commonly are referred to as the call letters of the stations. For stations regularly transmitting broadcast programs the call letters usually are three or four in number, and at the present time in the United States the first letter is either K or W.

This invention contemplates among other things the provision of means for tuning a radio receiver, such means including a pre-selector device, whereby any one of the stations whose programs are regularly received may be tuned in automatically merely by adjusting a plurality of pre-selector elements to display an arrangement of symbols representing the station. Such adjustment of the pre-selector elements may be accomplished in any suitable manner, dependent upon the form which the pre-selector elements take. In the illustrative embodiment the pre-selector elements are movable relative to a fixed reference mark. Conveniently the symbols are letters, and the receiver may be tuned automatically for the reception of currents from any selected station by adjusting the pre-selector elements to set up the call letters of the station.

Referring to the drawings for a further description of the illustrative embodiment, and first to Fig. 1, a cabinet 11 houses the radio receiver and the tuning apparatus. The cabinet has a front panel 12, and projecting forwardly through a series of parallel elongate openings 13 in the panel are the levers 14 which, as will appear hereinafter, are individually movable in a vertical direction to control the adjustment of the pre-selector elements. Above the slots 13 is an opening 15 through the panel 12, which opening frames a series of symbols, conveniently letters, which are borne by the pre-selector elements, and

which may be arranged by adjustment of the levers 14 to represent the call letters of a transmitting station whose signals are to be received. Desirably means such as the rotatable knob 16 5 also is provided for manual adjustment of the tuning mechanism of the receiver, and an opening 17 through the panel permits inspection of the usual reference scale which indicates visually the tuning adjustment of the receiver. Additionally, 10 the panel is provided with the usual volume and switch controls such as 18 and 19.

Referring to Fig. 2, each of the levers 14 is secured to the bottom of an elongate frame-like member 20, which members will be referred to herein as the pre-selector elements. These pre-selector elements may be made of any suitable material, for example, brass, and desirably the openings in the elements are filled with sheets of translucent material, each bearing a series of 20 symbols, for example letters. By adjusting the pre-selector elements vertically, the letters which are visible through the opening 15 in the front panel may be arranged in order as the call letters of a station whose currents are to be received. 25 The left hand pre-selector element in the illustrative embodiment bears only the letters K and W and a blank space, which for the reasons previously set forth is adequate for present usage in the United States.

Referring to Figs. 3, 4 and 5, it will be seen that the pre-selector elements 20 conveniently are secured against the rear of the panel 12 by means of a series of parallel T and L-shaped strips 21 secured to the panel in a suitable manner to provide channels in which the elements are free to slide. Desirably, stop means are provided to insure accurate framing of any letter on a pre-selector element in the opening 15 in the panel. Conveniently, such stop means comprise spring 30 members 22, (Fig. 4) in the sides of the channels for engaging notches 23, (Fig. 2) on the sides of the pre-selector elements 20.

In the illustrative embodiment, each pre-selector element 20 is provided at its upper end with 45 an electrical contact member which is mounted so as to be insulated electrically from the element. These contact members are designated on the drawings as 24, 25, 26 and 27, and an enlarged sectional view through one of the contact members is shown in Fig. 6. Conveniently each contact member comprises a barrel 28 secured, as by means of a screw-threaded connection, on an insulating stud 32 passing through the upper end of the pre-selector element 20. 50 The forward end of the barrel 28 has a sharp cutting edge 29, and inwardly of the cutting edge a restricted opening. A plunger contact 30 is urged resiliently outwardly through the open end of the barrel 28, as by means of a spiral compression spring 31 within the barrel. By reference to Figs. 2 and 4, it will be seen that the contact members 25 and 26 are offset laterally from the pre-selector elements in opposite directions, the reasons for which will appear hereinafter. 55 It will be noted that the stud 32 on which each of the contact members 24, 25, 26 and 27 is secured, slidably engages at its rear end either the panel 12 or one of the strips 21, thereby providing a rigid backing for the contact members. 60

As may best be seen in Figs. 2 and 3, in the 70 illustrative embodiment the plunger contacts 30 of the several members 24, 25, 26 and 27 are urged by the springs 31 against the face of a disk 40 which is mounted on the main tuning control shaft 41 of the radio receiver. The disk 40 is

keyed to the shaft 41 so as to turn therewith, but is mounted for sliding movement along the shaft. The disk 40 may be made of any suitable material, but in the illustrative embodiment is made of an insulating material such as fiber. 5 On the face of the disk engaged by the plunger contacts 30 are two washer-like rings 42 and 43 of conducting material separated by a narrow ring 44 of insulation. The dimensions of the rings 42 and 43 and the mounting of the contact members 10 24, 25, 26 and 27 on the pre-selector elements 20, are such that the plunger contacts 30 of the contact members 24 and 25 are pressed against the ring 42, and the plunger contacts 30 of the contact members 26 and 27 are pressed against 15 the ring 43.

Removably secured on the face of the disk 40 so as to turn therewith, and between the plunger contacts 30 and the conducting rings 42 and 43, is a sheet of insulating material 45, for example, 20 paper. As will be seen in Fig. 2, the sheet 45 has a number of small perforations 46 overlying each of the conducting rings 42 and 43. These perforations are arranged in predetermined combinations to permit all of the contact plungers 30 25 to project through the insulating sheet 45 and complete electrical contacts with the rings 42 and 43 for certain predetermined adjustments of the pre-selector elements 20 and corresponding adjustments of the tuning control shaft 41. The 30 manner in which these perforations may be located and made will be described hereinafter.

Referring to Fig. 2, the contact members 25 and 26 are connected electrically by means of a flexible jumper 50 which permits free adjustment 35 of each of the respective pre-selector elements 20. The contact member 24 is connected as by means of a flexible lead 51 to one terminal of a source of electric power. The contact member 27 is connected through the flexible leads 52, 40 a lamp 53, the lead 54, an electromagnet 55 and a lead 56 to the other terminal of the source of electric power. Energization of the electromagnet 55 attracts the armature 61 thereby opening an electric circuit comprising a motor, (not 45 shown) for adjusting the tuning control shaft 41, a suitable source of electric power, a lead 57, armature 61, lead 58, lamp 59 and lead 60 to the other side of the motor.

When the pre-selector elements 20 are arranged in such a manner that the contact members 24, 25, 26 and 27, register with perforations in the insulating sheet 45, an electrical circuit is completed from the source of power through the lead 51, contact member 24, ring 42, contact 55 member 25, jumper 50, contact member 26, ring 43, contact member 27, lead 52, lamp 53, lead 54, electromagnet 55 and lead 56 to the source of power. The lamp 53, which preferably is mounted in rear of the translucent sheets carried by 60 the pre-selector members 20 will be lighted, and the electromagnet 55 will be energized to open the circuit of the tuning control motor. The lamp 59 will be dark, and the adjustment of the tuning mechanism will not be changed until 65 either the shaft 41 or one or more of the pre-selector elements 20 are adjusted to disturb the electrical circuit for the electromagnet 55.

If it is desired to change the tuning of the receiver, the pre-selector elements 20 will be adjusted by moving the levers 14 until the letters visible through the opening 15 in the front panel are the call letters of the station whose program is to be received. It will be apparent that adjustment of the pre-selector elements opens the 75

5 circuit for the electromagnet 55 and the lamp 53. Thereupon, the armature 61 will be released and will complete an electrical circuit for the tuning motor, lighting the lamp 59. Conveniently, the lamps 53 and 59 may be of different colors, so that the light shining through the translucent sheets in the pre-selector elements, and visible through the opening 15 in the panel, will indicate the condition of the apparatus. For example, the lamp 53 may give a white light and the lamp 59 a red light.

10 If desired, means may be provided for preventing sounds issuing from the reproducer during the tuning operation. By way of example, the loud speaker may be short circuited, as by means of a contact member 62 carried by the armature 61, and engaging, when the electromagnet 55 is deenergized to release the armature, leads 63 connected to the terminals of the loud speaker, (not shown).

15 The tuning motor, (not shown) may be connected in any suitable manner to the control shaft 41, as by means of a frictional clutch arrangement, and when energized causes the shaft 25 41 to turn until a combination of perforations in the insulating sheet 45 register with the contact members 24, 25, 26 and 27 of the pre-selector elements. When such registration is secured, the electrical circuit for the lamp 53 and the electromagnet 55 is again completed, and the armature 30 61 is attracted to open the motor circuit and interrupt further adjustment of the tuning mechanism.

20 In many radio receivers in use at the present time, the tuning control shaft may be adjusted through an arc of only about 180°. Desirably means are provided so that if one limit of adjustment of the tuning mechanism is reached before obtaining registration of a combination of perforations in the insulating sheet 45 with the contact members 24, 25, 26 and 27, the tuning motor 40 will be automatically reversed in order to secure further adjustment of the tuning mechanism in the reverse direction until the aforesaid registration between the perforations and contact members is obtained.

25 For example, as shown in Fig. 2, the disk 45 may be provided adjacent its edge with two rearwardly projecting pins 47 and 48 arranged at diametrically opposite points. As the shaft 41 approaches one limit of its turning movement the pin 47 engages one end of a lever 80 which is pivotally mounted intermediate its ends at 80a. Also pivotally mounted at 80a is a switch arm 82. Means such as a compression spring 83 connecting the lever 80 and the switch arm 82 completes a toggle mechanism for turning the switch arm 82. Further turning of the shaft 41 actuates the toggle to shift the contact 81 on the end of the switch arm 82 from engagement with a contact 35 85 into engagement with a contact 84. The contacts 81, 84 and 85 are suitably connected by leads 86 to the tuning control motor so that actuation of the toggle switch reverses the motor. When the shaft 41 is turning in the opposite direction and approaches the limit of its turning movement, the pin 48 engages the lever 80 to 50 actuate the switch in a similar manner in the reverse direction to reverse the motor.

30 The insulating sheet 45 is secured on the face of the disk 40 so as to prevent relative turning movement, as by means of one or more screws 49, and the perforations 46 may be made in any convenient manner. In the embodiment of the invention disclosed the perforations 46 in the sheet

5 may be located and made in the following manner. The disk 40 is slidably mounted on the shaft 41, and normally is pressed rearwardly away from the contact members 24, 25, 26 and 27, as by means of a spring 64 pressed between the face of the disk 45 and a screw 65 in the end of the shaft 41. The rear of the disk is provided with a hub 66 having an annular channel 67 which is engaged, as at diametrically opposite points, by a yoke member 68. The yoke member 10 is pivoted at its lower end on a suitable support, conveniently a part of the frame supporting the rotatable shaft 41. Engaging the yoke 68 intermediate its ends, is a link 69, conveniently extending rearwardly through the back of the receiver and having at its end a push button 70, whereby the link may be manually actuated to cause the yoke 68 to move the disk 40 forwardly against the pressure of the spring 64 to press the sheet 45 against the cutting edges 29 of the 15 contact members 24, 25, 26 and 27.

20 By exerting pressure on the button 70, perforations will be made in the sheet 45, or alternately the sheet will be marked by the cutting edges 29 so that it can be subsequently perforated in some 25 other suitable manner. When the button 70 is released, the disk 40 is moved away from the contact members under the influence of the spring 64, and the punched-out portions of paper are pushed out of the ends of the contact members 30 by the plungers 30 under the influence of the springs 31.

25 It will be apparent that if, prior to actuating the perforating mechanism as above described, the pre-selector elements 20 have been adjusted 35 to show the call letters of a station whose currents are to be received, and the receiver has been tuned manually for the reception of currents from that station, it will be possible thereafter to tune the receiver for the reception of a program from the same station merely by adjusting the pre-selector elements to show the call letters 40 of the station. Obviously, by repeating this procedure for other transmitting stations, it will be possible to tune the receiver automatically for 45 any one of a limited number of stations whose programs are regularly received.

30 Manual adjustment of the tuning mechanism for the reception of currents from stations other than those regularly received, may be made in 50 the usual manner by means of any suitable mechanism, for example, by means of a disk 75 frictionally engaging the edge of the disk 40, and secured on the end of a control shaft 76 projecting through the panel 12 and carrying on its outer 55 end the knob 16. During operation of the receiver by manual tuning the tuning motor will be deenergized, as by opening a switch, (not shown) in the power circuit to the motor.

35 If the tuning control shaft 41 may be turned only through an arc of about 180°, the perforations in the sheet 45 will be arranged on substantially one-half of the sheet. The other half of the sheet 45 may be utilized, as shown in Fig. 2, 60 for a reference scale, a portion of which is visible through the opening 17 in the front panel to indicate the tuning of the receiver.

40 In the operation of the illustrative embodiment, the receiver is tuned manually to receive currents from a station whose programs are to be received 65 more or less regularly. The pre-selector elements 20 are adjusted to show the station call letters through the opening 15 in the front panel, and the button 70 is actuated to perforate the sheet 45. This procedure is repeated to perforate the sheet 75

for other stations for which it may be desired to tune automatically. The receiver may thereafter be tuned automatically for the reception of currents from any one of these stations by closing 5 the energizing circuit for the tuning motor and adjusting the pre-selector elements to display the call letters of the desired station.

The description of the illustrative embodiment is not intended as defining the limits of the invention, and it will be understood the invention may 10 be variously modified and embodied within the scope of the appended claims.

I claim:

1. In apparatus for receiving radiant energy, 15 the combination of tuning means, power means for adjusting the tuning means for the reception of currents of different frequencies, pre-selector means comprising a plurality of individually adjustable elements each bearing a plurality of letters, means for adjusting said elements with reference to a fixed mark to arrange in proper sequence the call letters of a selected transmitting station whose currents are to be received, and means operating automatically in response to 20 such adjustment to cause said power means to adjust said tuning means for the reception of the desired currents.

2. In apparatus for receiving radiant energy, the combination of tuning means, power means 30 for adjusting said tuning means for the reception of currents of different frequencies, pre-selector means comprising a plurality of elements each bearing a plurality of symbols, means for adjusting said elements to arrange a sequence of symbols representing a transmitting station whose currents are to be received, and means operative 35 automatically in response to the adjustment of said elements to cause said power means to adjust said tuning means for reception of the desired currents.

3. In apparatus for receiving radiant energy, the combination of tuning means, a motor for adjusting said tuning means, a plurality of pre-selector elements each bearing a plurality of symbols, means whereby said pre-selector elements 45 may be successively arranged in a plurality of different predetermined combinations of said symbols representing different transmitting stations, means including a relatively mobile perforated 50 element, controlled by said pre-selector elements and controlling said motor for automatically adjusting said tuning means to the predetermined position corresponding to any one of said several predetermined combinations of said pre-selector 55 elements which may be arranged.

4. In apparatus for receiving radiant energy, the combination of tuning means, a motor for adjusting said tuning means for the reception of currents of different frequencies, pre-selector indicating means comprising a plurality of adjustable letter-bearing members adapted to be arranged with reference to a fixed mark in a sequence representing the station call letters of a transmitting station whose signals are to be received, means controlled by said pre-selector 60 means for causing said motor to adjust said tuning means to a predetermined position for the reception of the desired signals, and for automatically interrupting further adjustment of said tuning means when said predetermined position is 65 reached.

5. In apparatus for receiving radiant energy, the combination of tuning means, a motor for adjusting said tuning means, a plurality of pre-selector elements, means whereby said pre-selector 70

elements may be successively adjusted to a plurality of different predetermined combinations representing different transmitting stations, means controlled by said pre-selector elements and controlling said motor for automatically adjusting said tuning means to the predetermined position corresponding to any one of said several predetermined combinations of said pre-selector elements which may be arranged, said last mentioned means comprising a plurality of electrical contacts and a relatively movable perforated sheet controlling the completion of an electrical circuit through said contacts.

6. In apparatus for receiving radiant energy, the combination of tuning means, station pre-selector means, means for adjusting said pre-selector means to establish an arrangement representing the call letters of a transmitting station whose signals are to be received, and motor circuit means including a disc perforated in a predetermined 20 manner, controlled by said pre-selector means, said pre-selector means including at least one contactor adapted to cooperate with at least one disc perforation to close said circuit for automatically adjusting said tuning means to the corresponding predetermined position for the reception of signals from the desired transmitting station.

7. In apparatus for receiving radiant energy, the combination of tuning means, means for adjusting said tuning means for the reception 30 of currents of different frequencies, a plurality of pre-selector elements bearing symbols and individually adjustable to bring the symbols into combinations representing different transmitting waves, means operative automatically when said pre-selector elements are arranged in a combination other than that corresponding to the adjustment of the tuning means to cause said second mentioned means to adjust said tuning means to a predetermined position for the reception 40 of the transmitting wave corresponding to said arrangement of the pre-selector elements, and means operative when said tuning adjustment is completed to discontinue further adjustment of said tuning means.

8. In apparatus for receiving radiant energy, the combination of tuning means, means for adjusting said tuning means for the reception of currents of different frequencies, a plurality of pre-selector elements bearing symbols and individually adjustable to a plurality of different predetermined symbol combinations representing different transmitting stations, an electrical circuit, means for changing automatically the characteristics of said electrical circuit when said pre-selector elements are arranged in a combination other than that corresponding to the adjustment of the tuning means, means operative upon such change in the characteristics of said electrical circuit to cause said second mentioned means to 50 adjust said tuning means to a predetermined position corresponding to said new arrangement of the pre-selector elements, means operative when said tuning adjustment is completed to again change the characteristics of said electrical circuit to their original condition, and means operative upon said last mentioned change in the characteristics of said electrical circuit to discontinue further adjustment of said tuning means.

9. In apparatus for receiving radiant energy, the combination of tuning means, means for adjusting said tuning means for the reception of currents of different frequencies, means for controlling said adjusting means comprising two se- 75

ries of electrical contact members, a sheet of insulating material having a plurality of perforations interposed between said two series of contact members, means for individually adjusting the contact members of one series relative to each other, and means operative automatically upon such adjustment of the contact members to adjust said tuning means and simultaneously move said perforated sheet to bring perforations in the latter into register with the adjusted contact members and complete an electrical circuit through said two series of contact members, and means operative thereupon to discontinue further adjustment of said tuning means and further movement of said sheet.

10 10. In apparatus for receiving radiant energy, the combination of tuning means, means for adjusting said tuning means for the reception of currents of different frequencies, means for controlling said adjusting means comprising a plurality of electrical contact members, a perforated sheet controlling the completion of an electrical circuit through said contact members, means for individually adjusting the contact members relative to each other, and means operative automatically upon such adjustment of the contact members to adjust said tuning means and simultaneously move said perforated sheet to bring perforations in the latter into register with the adjusted contact members, and means operative thereupon to discontinue further adjustment of said tuning means and further movement of said sheet.

20 11. In apparatus for receiving radiant energy, comprising station pre-selector means, tuning mechanism, an electrical control circuit for said tuning mechanism including a plurality of contacts in said pre-selector means, and a circuit determining sheet associated with said tuning mechanism, means for adjusting the tuning mechanism to receive desired currents, means for adjusting the pre-selector means to display a series of symbols representing the station transmitting the desired currents, and means for perforating the circuit determining sheet when said adjustments have been made.

25 12. In apparatus for receiving radiant energy, the combination of tuning means, means for adjusting said tuning means, a plurality of elements each bearing a plurality of symbols, means for

adjusting said plurality of elements individually to arrange a sequence of symbols representing a transmitting station whose currents are to be received, and means including a mobile perforated card for rendering said tuning adjusting means operative when said elements have been adjusted.

30 13. In apparatus for receiving radiant energy, the combination of tuning means, current consuming means for adjusting said tuning means for the reception of currents of different frequencies, station pre-selector means, a perforated disc for controlling said tuning adjusting means, means giving a signal during adjustment of the tuning means, means giving a different signal when the tuning means has been adjusted to a pre-selected position, said disc comprising a card provided with a plurality of apertures corresponding to different stations and contacts carried by said pre-selector means cooperating with the apertures in said card to control the current through said current consuming means.

35 14. The combination set forth in the preceding claim, in which the several means for giving different signals comprise differently colored lights.

40 15. In combination, in a radio receiver, a tuning means, power means for adjusting said tuning means, an electrical circuit including said power means, a plurality of independently vertically adjustable station pre-selector means arranged to render said electrical circuit operative at predetermined positions of said selector means, and a mobile card disposed in operative relation with said electrical circuit and said pre-selector means and including perforations arranged for controlling the operation of said power means.

45 16. In apparatus for receiving radiant energy, the combination of a tuning member, a plurality of independently adjustable station pre-selector means, means permitting the adjustment of said pre-selector means, means for automatically adjusting said tuning member in accordance with the adjustment of said pre-selector means comprising an electrical circuit and a circuit control disc adjustable with said tuning member, means for indicating continuously the adjustment of said tuning member, and means including an index carried by each of said pre-selector means for indicating the adjustment thereof.

ERNEST A. ZADIG. 50
